UNITED STATES PATENT OFFICE.

LEO A. CHMARA AND ANASTASIU A. CHMARA, OF BAY CITY, MICHIGAN.

RAIL-JOINT.

1,097,301.

Specification of Letters Patent. Patented May 19, 1914.

Application filed November 25, 1912. Serial No. 733,350.

To all whom it may concern:

Be it known that we, LEO A. CHMARA and ANASTASIU A. CHMARA, citizens of the United States, residing at Bay City, in the county of Bay and State of Michigan, have invented new and useful Improvements in Rail-Joints, of which the following is a specification.

Our invention relates to rail joints.

One object of our invention is to provide effective means to join or continuously connect complementary rails without the use of bolts or the equivalent fastening means.

Another object of the invention is to provide the means stated of such nature that a separate connecting member having means to interlock with the rail sections will be employed.

Further objects of the invention are to generally improve the construction of a joint of this kind.

The invention resides in the details of construction and combinations and novel arrangements of parts as shown in the drawings accompanying this application and hereinafter described.

In said drawings:—Figure 1 is a plan view illustrating the connecting means with complementary rails, the rails shown but fragmentarily. Fig. 2 is an elevation of the same parts. Fig. 3 is a cross sectional view of the line 3—3 of Fig. 1. Fig. 4 is a view partly in elevation and partly in section of a part of one of the rails constructed in accordance with our invention. Fig. 5 is an elevation of the connecting member employed. Fig. 6 is an end elevation of said connecting member, and Fig. 7 is an end view of one of the rails.

In the drawings, like reference characters designate like or similar parts throughout the views thereof.

Referring specifically to the drawings, A generally designates track rails and B generally designates the connecting member employed.

The rails at their ends are so formed as to provide a central longitudinal recess 2 and ribs 3, one on each side thereof. Into said recess 2 project and terminate short of its base, suitable teeth designated 4 which are preferably provided with an inclined face or wall 5 on one side thereof. The rail at the base flange is preferably cut away as at 6, for a purpose that will hereinafter appear. It will be noted that the teeth 4 do

not extend the full length of the recess, but terminate short of the ends of the rails so that a bearing face or surface 7 is provided. The ribs 3 at their base are preferably inclined as at 8. The rails at the ends are preferably somewhat enlarged.

The connecting member B is provided with a base web or plate 9 and with a rib 10 which rises centrally and vertically therefrom. Said rib 10 is provided with a plurality of teeth 11 which may have an inclined face or wall 12 similar to the walls 5 of the teeth 4. Centrally of the length of rib 10, the same is provided with a flat bearing surface 13. Grooves having inclined bottom walls are provided on the base plate or flange 9.

In use, the connecting member B is first positioned. Thereupon, the complementary rails are connected thereto. During the connecting action, the rails are moved to position over the connecting member where the teeth 4 can move or slide into the notches intermediate teeth 11. When the teeth slide into the notches, the beveled or inclined walls 5 ride on the beveled or inclined walls 12, whereby the teeth will slide easily into inter-engagement. When the teeth have become thus engaged, the surfaces 7 will rest or bear upon the surface 13 and the base plate or flange 9 will be received in the cut out portions 6 of the rails. By reason of the inclination of walls 8 and 14, the connecting member and sections will be prevented from moving or being jarred laterally.

As merely the preferred form of the invention has been shown and described, such changes as fall within the spirit and scope of the appended claims are reserved.

Having thus described our said invention, what we claim as new and desire to secure by Letters Patent, is:—

1. In combination with rail members, a rail connecting member, an enlargement formed upon the extremity of each of the said rail members, each enlargement being cut away at the base thereof, teeth formed integrally with the said rail member adapted to depend into the said cut away portion, the teeth of one rail member extending oppositely to the teeth of the other, a rib formed upon the said connecting member disposed to fit the said cut away portion, inclined surfaces formed upon the connecting member adapted to form seats for in-

- clined faces formed upon the said enlargement, teeth formed integrally with the connecting member, the teeth upon one end thereof being inclined oppositely to the teeth upon the other, the teeth upon each end adapted to mesh into the corresponding teeth formed upon the rail member to fasten the said members together, as and for the purpose set forth.
- 10 2. In combination with rail members, a rail connecting member, enlargements formed upon the extremities of the said rail members, the said enlargements being cut away at the base thereof, a longitudinally extending recess open to the said cut away portion, teeth formed integrally with the said rail member adapted to depend into the said recess, a longitudinally extending rib formed integrally with the said connecting

member, inclined surfaces formed upon the said connecting member adapted to form seats for inclined faces formed upon the said enlargement a flat bearing surface formed centrally upon the said rib, teeth formed integrally with the said rib upon each side 25 of the said flat bearing surface, the teeth upon one side of the said surface being inclined oppositely to the teeth upon the other, the teeth upon each side adapted to mesh into the corresponding teeth formed upon 30 the rail members for fastening the said members together, as and for the purpose set forth.

LEO A. CHMARA.

ANASTASIU A. CHMARA.
